CLAIM

The ornamental design for faucet, as shown and described.

DESCRIPTION

FIG. 1 is a perspective view of our new design of a faucet; FIG. 2 is a front elevational view of our new design of the faucet;

FIG. 3 is a rear elevational view of our new design of the faucet;

FIG. 4 is a right side elevational view of our new design of the faucet, a left side elevational view thereof being a mirror image of the right side elevational thereof;

FIG. 5 is a top plan view of our new design of the faucet; and,

FIG. 6 is a bottom plan view of our new design of the faucet. The broken line showing is for illustrative purposes only and forms no part of the claimed design.
